UNITED STATES PATENT OFFICE.

JESSE M. SPROAT, OF NORTH BENTON, OHIO.

SAP-BOILING APPARATUS.

SPECIFICATION forming part of Letters Patent No. 318,815, dated May 26, 1885.

Application filed March 5, 1885. (No model.)

To all whom it may concern:

Be it known that I, JESSE M. SPROAT, a citizen of the United States, residing at North Benton, county of Mahoning and State of Ohio, have invented certain new and useful Improvements in Sap-Boiling Apparatus; and I do hereby declare the following to be a description of the same, and of the manner of constructing and using the invention, in such full, clear, concise, and exact terms as to enable any person skilled in the art to which it app pertains to construct and use the same, reference being had to the accompanying drawing, forming a part of the specification, the principle of the invention being herein explained and the best mode in which I have contemplated applying that principle, so as to distinguish it from other inventions.

My invention is an improvement in sap-boiling apparatus, and is designed to facilitate the process of boiling by heating portions of the sap before it is put into the boilers by means of heat from the boiler.

The drawing is a vertical sectional view of my device, showing it as in use.

A is the furnace, with chimney a.

B is the boiler, seated upon the furnace, and has the top B' detachable, but so shut down by means of flanges around the top edge of the boiler as to confine the vapor of the boiling sap sufficiently for the purposes of my device, and is provided with the open-top cone d.

C is the heater, seated upon said top and provided with the separate chambers C', D, and E. The bottom of heater C is convex and provided with central opening, b, through which cone d projects.

C' is the sap-heating chamber, and is traversed by the flues e, which open at their respective ends into chambers D and E.

Chamber E is provided with the discharge-pipe e, opening from the top E', and projecting downward into the furnace. Said pipe has the slip-joints e' and e'', adapting it to be shortened or lengthened as desired. The flues e may be of any desired number. The design of pipe e is to convey away the vapor of the boiling sap after it has reached chamber E.

Chamber C' is provided with the supply-

pipe F, having funnel f and stop-cock f', and the discharge-pipe G, the latter having stop-cock g. Through pipe F sap is introduced into chamber C' to be heated, and through pipe G it is drawn off into the boiler.

Top E' is formed conical; but I am not confined to that form, and the top may be of any preferred form. Neither am I confined to the termination I have given to pipe e; but it may have any preferred direction and termination.

It is well known that the escape of the vapor from boiling sap out into the building where the process is going on is objectionable; hence the utility of my device for conducting it away outside the building. In addition to this I utilize the passing vapor for heating the sap in chamber C' by heating it in chambers D and E, and by passing it through the flues e. Also, I do not confine my device of top E' with pipe e, having the slip-joints e' and e'', to sap-boiling apparatus; but it may be applied equally well to other similar processes, and to diverse articles of analogous use, such as the kettles of an ordinary domestic stove. Said top device can also be utilized for the ventilation of rooms or even houses.

What, therefore, I claim is—

1. In a sap-boiling apparatus, the combination, with boiler B, of sap-heater C, operatively connected with said boiler and provided with sap-holding chamber C', located between vapor-chambers D and E, said vapor-chambers connected together by flues e, traversing chamber C', said combination adapted to heat the sap in the latter chamber by the vapor in chambers D and E and flues e, substantially as set forth.

2. In a sap-boiling apparatus, the combination, with boiler B, of sap-heater C, operatively connected with said boiler, said heater having the chambers D and E, connected together by flues e, and having also sap-chamber C', located between the chambers D and E, said chamber C', traversed by flues e and provided with supply-pipe F and discharge-pipe G, chamber E, having outlet-pipe e, connecting with furnace-draft, said pipe having slip-joints e' e'', all for the purposes set forth and described.

3. In a sap-boiling apparatus, the combina-

tion, with the boiler, of heater C, operatively connected with said boiler, said heater having the vapor-chambers D and E, connected together by suitable vapor-conducting devices, 5 said heater having also the sap-holding chamber C', located between chambers D and E and in operative connection with said vapor-conducting devices, chamber E being provided with escape-pipe e, discharging into the 10 furnace-draft, substantially as set forth.

4. In a sap-boiling apparatus, the combination, with heater C, of the detachable top E, having the discharge-pipe e, provided on its horizontal arm with slip-joint e' and on its 15 vertical arm with slip-joint e'', substantially as set forth.

5. In a sap-boiling apparatus, the combination, with boiler B, having top B', provided with open-top cone d, of heater C, having a convex bottom provided with aperture b, 20 through which said cone projects, substantially as set forth.

6. The conical top E', provided with an escape-pipe emptying into a furnace-draft, substantially as set forth.

In testimony that I claim the foregoing to be my invention I have hereunto set my hand this 20th day of February, A. D. 1885.

JESSE M. SPROAT.
